UNITED STATES PATENT OFFICE

JOHN S. HANSEN, DECEASED, LATE OF BROCKTON, MASSACHUSETTS, BY ELWINE G. HANSEN, EXECUTRIX, OF BROCKTON, MASSACHUSETTS, ASSIGNOR TO O. A. MILLER TREEING MACHINE COMPANY, OF PORTLAND, MAINE, A CORPORATION OF MAINE

SHOE FORM

Application filed April 27, 1925. Serial No. 26,111.

This invention relates to shoe trees and stretchers and is illustrated as embodied in a tree to be used for keeping shoes in shape during periods when they are not being 5 worn.

It is commercially important that such forms be inexpensive and, in order to secure the requisite quantity production of each size of form, the number of different sized 10 articles corresponding to a line of sizes and widths of shoes must be very small. Accordingly, and in order that the use of such forms may be economical to the purchasers, the same form or tree should serve for numerous 15 different styles and sizes of shoes. In view of these considerations, such a form should be adjustable for length and should have a considerable range of expansion in its forepart. Such forms or trees are therefore often found provided with a split expansible forepart which is operated by throwing a longitudinally expanding toggle which unites the forepart and the heel part: the length adjustment being advantageously secured by making this toggle adjustable in 20 length.

A considerable number of devices for expanding the forepart members have appeared. They generally involve a pair of 30 toggle links connecting the forepart member to the operating member, or a plate with converging slots operating on pins in the forepart members, or vice versa. Such devices have all failed to give satisfaction, because, among other reasons, they do not provide for 35 keeping the forepart members in alinement; they separate them, it is true, but there is nothing to prevent one forepart member from running into the shoe ahead of the other, and remaining so relatively displaced. This sort 40 of performance frequently occurs and pulls the shoe out of shape.

It has been attempted to meet this difficulty by inserting a wire nail horizontally 45 transversely in the toe ends of the forepart members, the head end of the nail being slideable in its forepart member. This construction, however, often sticks and gives a great deal of trouble.

50 It is a principal object of the invention

to overcome this and other difficulties, by the provision of means for holding the forepart members in proper alinement at all times, so that they will always move evenly into the shoe. As disclosed, this means comprises a 55 plate attached to the forepart members so as to prevent relative longitudinal displacement, and cooperating with the toggle member to maintain the proper alinement.

It is a further object of the invention to 60 provide an improved adjustable toggle mechanism for expanding the tree. A feature of the invention in this aspect consists in an adjustable pivot pin for the toggle having a rebent end engageable with any one of a 65 plurality of notches in the side of a slot in a toggle link along which the main body of the pin is movable.

These and other features of the invention 70 comprising certain combinations and arrangements of parts will be understood from the following description of a preferred embodiment thereof selected for purposes of illustration and shown in the accompanying drawings in which,

Fig. 1 is a perspective view of the tree.

Fig. 2 is a vertical section on the plane indicated by 2—2 in Fig. 1.

Fig. 3 is a horizontal section on the line 3—3 of Fig. 2.

Fig. 4 is a vertical section on the line 4—4 of Fig. 3.

Fig. 5 is a similar section showing the toggle unlocked.

Fig. 6 shows the two plates used in the 85 tree.

The forepart is split into two members 10 by a vertical longitudinal cut. The inner faces of these members are slotted at 12 and cut away at 14 to receive the operating 90 means. These means comprise a spreader plate 16 having at its forward end a pair of forwardly converging slots 18 each engaging a pin 20 in one of the forepart members 12. It is clear that projecting the plate 16 forward and backward will spread and retract the forepart members respectively.

In a hole 22 at the rear end of the plate 16 is pivotally mounted the front end of the toggle link 24. This link is punched 100

and slotted at its front end as at 26 to receive the tongue which lies to the rear of the hole 22, and the slot is then pounded shut in assembling the device.

5 The link 24 is slotted as at 28, and the bottom of the slot is extended in a number of semi-circular depressions or notches 30. The link 24 is embraced by a sleeve 32 arranged to slide along it. The sleeve fits the 10 link 24 vertically, but provides an opening about twice as thick as the link 24, and is open at one side of its bottom, as at 34.

15 The sleeve carries a pin 36 which is rebent upon itself at 38, and can slide back and forth laterally through the sleeve, the holes in the sides thereof fitting the single and the double portions respectively of the pin. A spring 40 resting against the sleeve and the head 41 of the pin tends to push the pin to 20 the right in Fig. 4. The main part of the pin is in alignment with the slot 28, and the rebent part with the notches 30. When the parts are in the position shown in Fig. 4, the sleeve 32 is locked on the link 24; when 25 the pin is thrown to the left as in Fig. 5, the portion 38 slides out of the notch 30 and the sleeve can be adjusted back and forth on the link to set the pin into another of the notches 30.

30 A second toggle link 42 is pivoted on the pin 36 inside the sleeve, beside the link 24, and is permitted to swing downwardly around the pin as shown in Fig. 1 through the opening 34. It can swing upwardly 35 around the pin to a slight extent before coming in contact with the upper side of the sleeve, the pin hole in the link 42 being somewhat above center in order to effect this. The heel part 44 is fastened to the 40 rear end of the link 42.

The pin 36 being in any desired position of adjustment, the device is inserted in the shoe with the forepart members closed together and the toggle bent with the heel 45 part down in the heel end of the shoe, and the straightening of the toggle forces the forepart into the shoe and spreads it. The link 42 can swing upwardly beyond alignment with the link 24 sufficiently to bring 50 the pivot pin 36 below the line joining the outside ends of the toggle links so that the device will stay in place under pressure. The length of the toggle can be adjusted to the shoe by putting the pin 36 into the proper 55 notch 30. A thumb piece 46 is provided on the sleeve to assist in throwing the toggle.

So far nothing has been described which will prevent the forepart members having a dissimilar or uneven movement when the 60 tree is forced into the shoe, and the means for accomplishing this result forms an important feature of the invention.

This means, in the embodiment of the invention shown, consists of a plate 48 having 65 a longitudinal slot 50 at its rear end and

two transverse slots 52 in its forward portion. The pins 20 pass through the slots 52 and the link 24, which is here formed as a vertical flat plate, plays in the slot 50. The link and plate can turn relatively in a vertical plane 70 and slide relatively in a horizontal plane, but no substantial horizontal relative rotation is possible. Thus the pins 20 will always be kept on a line perpendicular to the link 24, though the distance of this line from the end of the link will vary as the pins are moved toward and from each other by the advance and retraction of the link 24 and spreader plate 16. The forepart members can thus pivot 75 about the centers of the pins 20 as they are separated to fit the contour of the shoe, but are always held in transverse alignment, since neither pin 20 can get ahead of the other. In other words the horizontal orientation of the forepart members relatively to the heel part 80 is preserved.

Having described the invention, what is claimed as new and desired to be secured by Letters Patent of the United States is:—

1. A shoe tree comprising a forepart and a heel part and a toggle mechanism connecting them comprising two flat links side by side, a sleeve embracing their adjacent ends, and a pivot pin mounted in the sleeve and pivoted in one of the links and adjustable along the 95 other link.

2. A shoe tree comprising a forepart and a heel part and a toggle mechanism connecting them comprising two flat links side by side, a sleeve sliding along one of the links, and a 100 pin mounted in the sleeve arranged for adjustable connection to the last-mentioned link, the other link being pivoted to the pin.

3. A shoe tree comprising a forepart and a heel part and a toggle mechanism connecting them comprising two flat links side by side, one of said links having a longitudinal slot with notches on one side of it, and a pin 105 in the slot with a rebent end arranged to enter one of the notches, the second link being pivoted to the pin.

4. A shoe tree comprising a forepart and a heel part and a toggle mechanism connecting them comprising two flat links side by side, one of said links having a longitudinal slot 115 with notches on one side of it, and a sleeve sliding along this link carrying a pin slideable transversely through it, the pin passing through the slot and having a rebent end engaging a said notch and being removable 120 from said notch by sliding the pin in the sleeve, the second toggle link being pivoted to the pin.

5. A shoe tree comprising a forepart and a heel part and a toggle mechanism connecting them comprising two flat links side by side, one of said links having a longitudinal slot with notches on one side of it, and a sleeve sliding along this link carrying a pin 125 slideable transversely through it, the pin pass- 130

- ing through the slot and having a rebent end engaging a said notch and being removable from said notch by sliding the pin in the sleeve, the second toggle link being pivoted to the pin, the sleeve encircling the links except at a point below the second link. 5
6. A shoe tree comprising a forepart and a heel part and a toggle mechanism connecting them comprising two flat links side by side, 10 one of said links having a longitudinal slot having one side straight and the other side plurally notched, and a pin in the slot with a rebent end arranged to enter one of the notches, the second link being pivoted to the pin. 15
7. A shoe tree comprising a forepart and a heel part and a toggle mechanism connecting them comprising two flat links side by side, one of said links having a longitudinal slot 20 having one side straight and the other side plurally notched, and a pin with a rebent end in the slot, the rebent end of the pin being arranged to enter one of the notches and the body of the pin being arranged to slide along 25 the straight side of the slot. 25
8. A shoe tree comprising a forepart and a heel part and a toggle mechanism connecting them comprising two flat links side by side, one of said links having a longitudinal slot 30 having one side straight and the other side plurally notched, and a pin with a rebent end in the slot, the rebent end of the pin being arranged to enter one of the notches and the body of the pin being arranged to slide along 35 the straight side of the slot, the rebent end of the pin being disengageable from the notch by virtue of longitudinal movement of the pin. 35
9. A shoe tree having a heel part and two 40 complemental forepart members, and means for spreading the forepart members and for maintaining their horizontal orientation relatively to the heel part. 40
10. A shoe tree having a heel part and two 45 complemental forepart members, means for spreading the forepart members, and a member for maintaining their horizontal orientation relatively to the heel part. 45
11. A shoe tree having a heel part and two 50 complemental forepart members, means for spreading the forepart members, a pin in each forepart member, and means engaging the pins to maintain the horizontal orientation of the forepart members relatively to the 55 heel part. 55
12. A shoe tree having a heel part and two 60 complemental forepart members, means for spreading the forepart members comprising a toggle, a pin in each forepart member, and means for keeping the pins on a line perpendicular to the toggle. 60
13. A shoe tree having a heel part and two 65 complemental forepart members, means for spreading the forepart members comprising a toggle, a pin in each forepart member, and a 70
- plate engaging the pins and the toggle constructed and arranged to keep the pins on a line perpendicular to the toggle. 75
14. A shoe tree having a heel part and two complemental forepart members, means for spreading the forepart members comprising a toggle, a pin in each forepart member, and a plate engaging the pins and having a longitudinal slot at its rear end engaging the toggle. 75
15. A shoe tree having a heel part and two complemental forepart members, means for spreading the forepart members comprising a toggle, a pin in each forepart member, a plate having opposite transverse slots engaging the pins permitting movement of the pins toward and from each other to spread the forepart members, and a longitudinal slot at its rear end slidably engaging the toggle. 80
16. A shoe tree having a heel part and two complemental forepart members, a pin in each forepart member, a spreader plate engaging the pins, a toggle mechanism connecting the spreader plate and the heel part for spreading the forepart members, and a second plate having collinear slots engaging the pins respectively, and having also a slot at its rear end slidably engaging the toggle mechanism to hold the collinear slots perpendicular to the longitudinal axis of the tree. 85 90
17. A shoe tree comprising a forepart and a heel part and a toggle mechanism connecting them comprising two flat links side-by-side, one of said links having a slot with alternate enlarged and reduced portions, a member embracing the adjacent ends of the links, and a pivot pin mounted in the member, pivoted in the unslotted link and adjustable along the slot in the slotted link. 95 100
18. A toggle mechanism for a shoe tree comprising two flat links arranged side-by-side with an end of each adjacent an end of the other, one of said links having a slot with alternate enlarged and reduced portions, a sleeve embracing the adjacent ends of the links, and a pivot member having an enlarged and a reduced portion corresponding to the said portions of the slot, respectively, said pivot member being mounted in the sleeve, pivotally mounted in the link not described as slotted, and extending through the slot in the slotted link. 110 115
19. A toggle joint for shoe trees comprising an arm provided with a slot having alternate enlarged and reduced portions, a slider on said arm, a pivot member provided with an enlarged and a reduced section supported on said slider and extending through said slot, an arm pivoted on said pivot member guided for pivotal movement by said first mentioned arm and said slider, and a spring normally holding the enlarged section of said pivot member in an enlarged portion of said slot, the parts being so proportioned and arranged that said slider together with said 120 125 130

pivot member and said pivoted arm are movable along said slot only when the reduced portion of said pivot member is moved into said slot.

⁵ In testimony whereof I have signed my name to this specification.
